ELECTRIC LAMP CORD TAKE-UP

Eugene J. Todd, Lansdowne, Pa.

Application December 26, 1933, Serial No. 704,025

1 Claim. (Cl. 242—107)

The invention relates to an electric lamp cord take-up and more especially to a device for fitting within the base of a portable electric lamp to function as an electric cord take-up.

5 The primary object of the invention is the provision of a device of this character, wherein a reel carrying a stud journal is susceptible of fitting within the base of a portable electric lamp, either table, floor or other style of lamp, so that 10 the electric cord as trained through the base can be taken up automatically or permitted to feed therefrom corresponding to the length of said cord, thereby eliminating the unsightly appearance of such cord in its length being exposed 15 outside of the base and thus relieving wear upon the cord with the liability of short circuiting as oftentimes happens where the cord is permitted to rest upon a floor.

Another object of the invention is the provision 20 of a device of this character, wherein the reel for the electric cord is controlled by a ratchet so that such reel can be locked for permitting variation in the extent of the electric cord for the lamp when the same is fed from the base or taken up 25 therein, the device being novel in construction and adaptable for fitting within the lamp base so that it will be concealed thereby and free from being tampered with.

A further object of the invention is the provision 30 of a device of this character which is simple in construction, thoroughly reliable and efficient in its purpose, readily and easily applied to and removed from the base of an electric lamp, strong, durable, and inexpensive to manufacture 35 and install.

With these and other objects in view, the invention consists in the features of construction, combination and arrangement of parts as will be hereinafter more fully described in detail, illustrated 40 in the accompanying drawing, which discloses the preferred embodiment of the invention, and pointed out in the claim hereunto appended.

In the accompanying drawing:

45 Figure 1 is a fragmentary vertical longitudinal sectional view through a lamp support showing the device constructed in accordance with the invention applied to its base and the electric cord wound upon the reel of the device.

50 Figure 2 is a horizontal sectional view through the base, showing the reel of the device partly broken away.

55 Figure 3 is an enlarged fragmentary sectional view showing the ratchet in latching position with relation to the reel of the device.

Figure 4 is a view similar to Figure 3, showing the automatic release of the ratchet.

Figure 5 is a vertical sectional view through a modified form of reel.

Similar reference characters indicate corresponding parts throughout the several views in the drawing.

Referring to the drawing in detail, A designates generally a portion of the base of a portable electric lamp having the tubular staff or standard B through which is trained the electric cord for current to the lamp. The base is of truncated frusto-conical shape and has the hollow or chamber 10 in the lower side or bottom thereof for accommodation of the device constituting the present invention and hereinafter fully described.

The device comprises a reel made up of the spaced matched upper and lower disks 11 and 12, respectively, between which and at the center 20 thereof is the hub 13, the latter, by a set screw 14, being made fast to a stud journal 15, the disks being free of the said hub 13 and the journal 15. This journal 15 is formed with the threaded end 16 so that it can be tapped into the base A vertically centered with the staff or standard B.

Concentrically to the hub 13 and between the disks 11 and 12 is a ring member 17 which is fixed to the disks by the fasteners 18 and about this ring member is coiled the electric cord C, the latter 30 being delivered into and between the disks through the opening 19, while such cord is fed from the reel and taken up thereon through a tangentially disposed outlet 20 formed in the base A, the said outlet being capped by an insulated 35 sleeve 21 through which said cord passes. It is, of course, understood that the outer end of the cord is equipped with an electric plug terminal (not shown).

Superimposed upon the disk 11 and about the 40 stud journal 15 is a collar 22 which is made fast to the reel by being secured in any desirable manner to the said disk 11, and in a suitable cut-out portion, as at 23, in said collar is arranged a ratchet dog 24 pivoted at 25 in said collar, the 45 dog being formed with a square-cornered bight 26 and a tapered nose extension 27, the bight 26 being adapted to gravitate into one of a pair of diametrically opposed ratchet notches 29 in the hub 13, each notch being confronted with a cam 50 face or bevel 30 for coaction with the bight 26 of the dog 24, whereby on the turning of the reel the same may be latched at intervals by the dog 24 and the latter automatically tripped for the further turning of such reel. The nose 27 merely 55

serves to limit the dropping of the bight 26 into the notch 29.

Located between the hub 13 and the ring member 17 is a coiled tensioning spring 31, one end being fastened to the said hub and the other to the ring member 17 and this spring 31 functions as a winder, it being tensioned on the letting out of the cord C and operating to take up and wind the cord upon the reel on the release of the latter from the dog 24.

It should be clearly apparent that the cord C for the lamp will be automatically taken up or permitted to be fed outwardly at variable lengths at the option of the user of the lamp.

When disengagement of the dog 24 from the notch 29 is required it is necessary to pull upon the cord C and then suddenly release the said cord; on the pulling of the cord the edge a of the notch will kick upon edge b of the dog throwing the latter upwardly and by the sudden release of said cord this dog will be caused to trip over the notches 29 as the bevel 30 affords a riding surface for the bight 26 to prevent such bight falling within the notches 29 under the rapid turning of the reel.

The base A at the hollow 10 has the internal shoulder 32 confronting the open periphery of the reel in close proximity thereto so as to avoid any possibility of the cord working off of the reel in the operation of the device.

In Figure 5 of the drawing there is shown a slight modification, wherein the reel includes the upper and lower spaced parallel disks 33 and 34, respectively, these concentrically with respect to their centers being inwardly struck to provide inset annular abutments 35 contacting with each

other and united by rivets or other fasteners 36, thereby uniting these disks 33 and 34 with each other.

The hub 37, between the disks 33 and 34, is made fast to the stud journal 38 and this, with the journal 15 at its outer end, has a screw driver slot 39 for convenience in fastening the said journal within the base of a lamp.

It will, of course, be understood that the cord may be pulled outwardly to its fullest extent and also shortened as the occasion may require and such cord will be held in its adjusted position.

What is claimed is:

A device of the kind described comprising a stud journal engaged with the inner portion of the base of an electric lamp having a chamber opening through the bottom of said base, a hub removably and adjustably secured on said stud journal, a reel within the chamber for accommodating an electric current cord for the lamp for the winding of the cord on and from said reel and including spaced disks located at opposite sides of the hub and joined with each other inwardly of the outer peripheries of the same to have the cord outwardly of the points of juncture of the disks, a winding spring about the hub and between the disks inwardly of the points of juncture thereof and having one end fixed to the hub and the other end fixed to said reel, and a ratchet device carried by the reel and coacting with the hub for latching action of said reel, said chamber having a wall concentric of and close to the outer periphery of the reel to prevent the riding off of the cord from said reel.
